US00D958937S

(12) **United States Design Patent** (10) **Patent No.:** **US D958,937 S**
Pfund et al. (45) **Date of Patent:** **** Jul. 26, 2022**

(54) **HOUSING FOR MULTIPLE VALVES**

(71) Applicant: **Bradley Fixtures Corporation**,
Menomonee Falls, WI (US)

(72) Inventors: **Ryan Pfund**, Menomonee Falls, WI
(US); **Heming Dai**, Menomonee Falls,
WI (US)

(73) Assignee: **Bradley Fixtures Corporation**,
Menomonee Falls, WI (US)

(**) Term: **15 Years**

(21) Appl. No.: **29/779,384**

(22) Filed: **Apr. 19, 2021**

(57) **CLAIM**

We claim the ornamental design for a housing for multiple valves, as shown and described.

DESCRIPTION

FIG. 1 is a front, right, perspective view of the claimed design, additionally showing an exemplary pair of valves attached to the housing;

FIG. 2 is a front, right, perspective view of the claimed design of FIG. 1;

FIG. 3 is a front side view thereof;

FIG. 4 is a rear side view thereof;

FIG. 5 is a right side view thereof;

FIG. 6 is a left side view thereof;

FIG. 7 is a top view thereof; and,

FIG. 8 is a bottom view thereof.

The broken lines in the drawings illustrate environmental structure and form no part of the claimed design.
